UNITED STATES PATENT OFFICE.

EUGENE D. LEWIS, OF BESSEMER, ALABAMA.

RADIATOR COVER.

Application filed November 21, 1923. Serial No. 676,129.

To all whom it may concern:

Be it known that I, EUGENE D. LEWIS, a citizen of the United States, residing at Bessemer, in the county of Jefferson and State of Alabama, have invented a new and useful Radiator Cover, of which the following is a specification.

This invention relates to covers for hot air, hot water, and steam radiators.

10 The object of the invention is to provide a simple and efficient cover for radiators of the class described which will artistically conceal the radiator and cause it to harmonize with the other furniture.

15 Another object is to so construct and arrange such a cover that it will increase the efficiency of the radiator and prevent discoloration of the wall by the heat from the radiator.

20 Another object is to provide a cover for radiators which will prevent freezing of the water in the radiator when exposed to low temperatures, such as obtained in sleeping rooms in cold climates when the windows are left open for ventilation.

25 With the foregoing and other objects in view which will appear as the description proceeds, the invention resides in the combination and arrangement of parts and in 30 the details of construction hereinafter described and claimed, it being understood that changes in the precise embodiment of the invention herein disclosed, may be made within the scope of what is claimed without departing from the spirit of the invention.

In the accompanying drawings:

Figure 1 represents a front elevation of a radiator cover constructed in accordance 40 with this invention.

Fig. 2 is a horizontal section taken on the line 2—2 of Fig. 1; and

Fig. 3 is a transverse vertical section taken on the line 3—3 of Fig. 1.

45 In the embodiment illustrated the cover 1 constituting this invention is shown applied to a radiator R of ordinary construction such as is used for hot water or steam and over which is placed the cover referred to. This cover 1 is shaped to conform to the shape of the radiator and the rear wall 2 thereof extends to the bottom of the radiator and fits snugly against the floor F. The front wall 3 and the end walls 4 and 5 terminate short of the floor F leaving sufficient space for the ingress of the cold air

and the front wall 3 has an opening 6 of about one and one-half inches more or less located beneath the cover 10 at the top to form a flue for the egress of hot air.

60 The top or lid 10 overhangs the front and end walls of the casing 1 and has a depending hood-like flange 11 at the front which conceals the opening 6 and which is bent to form a deflector which directs the hot air emanating from opening 6 out into the room and prevents it going directly upward and carrying with it dust and the like. This cover 10 is hinged at 12 to the rear wall 2.

65 The front, back and end members are preferably constructed from sheet metal and are assembled and held in position by right angularly bent lips 7 which overlap adjacent portions and are held in position by 70 any suitable means such as soft welding or bolts, the latter being here shown. The top or cover 10 as well as the end and back walls of the casing are constructed of two plies of sheet metal with sheet asbestos arranged between them which prevents the 75 top and walls from heating. This will facilitate the use of the top as a stand or table for holding flowers, magazines, and the like and will prevent a current of hot air from 80 passing up the wall adjacent which such radiators are usually located, said current usually carrying with it dust from the room which settles on the top of the radiator and which discolors walls and draperies above the radiator.

85 The front wall 3 which is made of a single sheet of metal is provided at its upper portion directly below the opening 6 with a plurality of apertures 3^a which are of sufficient size and number taken in connection with opening 6 to permit the egress of all the hot air radiated from the radiator. These combined openings comprise an outlet flue for the hot air generated by the radiator. The wall 3 below the opening 3^a and above the lower edge of said wall is imperforate throughout. The opening below the plate 3 forms a draft opening similar to the draft door of a stove thereby ensuring a 100 perfect circulation and draft through the radiator covering and which forces the heat out through the openings in the top into the room projecting it for a distance of twenty-eight inches more or less, thus distributing 105 the heated air over a large area at a low point so that a room will be heated with a 110

radiator having this cover several minutes quicker than without the cover. The end members 4 and 5 are provided with openings as 8 near the bottom to permit an operator to obtain access to the radiator valves for turning on and off the heat.

A metal deflector 9 is secured to the inner face of the rear wall 2 and is curved upwardly and forwardly over the radiator R 10 and is designed to facilitate the egress of the hot air through the opening 6 by directing it toward this opening and which also prevents the top of the radiator from heating.

15 The entire casing will preferably be finished in standard colors of enamel baked to a temperature sufficient to withstand the heat of the hottest radiator. These covers or casings which are made in standard sizes 20 can be fitted over pipe fittings in the radiator at any time since the baked enamel finished sheet metal can be readily cut with a pair of snips. Moreover a baked enamel finish is desirable from an artistic standpoint 25 since it can be made dull or gloss to harmonize with the furniture in the room. It will also stand shipping and installing without breaking or scaling off.

I claim:—

A radiator cover comprising a casing 30 shaped to conform to the radiator in connection with which it is to be used, said casing having an imperforate rear wall extended to and fitting snugly against the floor while the end walls thereof have openings 35 at their lower ends for the ingress of cold air, a top for said casing overhanging the end and front walls of the casing, said front wall having an opening at its upper end and located under and concealed by the over- 40 hanging top, the end, rear, and top walls of the casing being asbestos lined and air-tight to conserve the heat and direct it through the opening in the front wall, a deflector for directing the heat out through said openings, 45 said front wall having apertures adjacent said opening and imperforate below said apertures, the lower end of said front wall having a draft opening whereby a perfect and complete circulation and draft through 50 the casing is provided.

In testimony that I claim the foregoing as my own, I have hereto affixed my signature.

EUGENE D. LEWIS.
